UNITED STATES PATENT OFFICE.

EZRA SANGER BUCKNAM, OF PHILADELPHIA, PENNSYLVANIA, ASSIGNOR
TO JOHN A. BRILL, OF PHILADELPHIA, PENNSYLVANIA.

CONVERTIBLE RAILWAY-CAR.

SPECIFICATION forming part of Letters Patent No. 709,075, dated September 16, 1902.

Application filed December 16, 1901. Serial No. 86,019. (No model.)

To all whom it may concern:

Be it known that I, EZRA SANGER BUCKNAM, a citizen of the United States, and a resident of the city and county of Philadelphia, State 5 of Pennsylvania, (whose post-office address is care of the J. G. Brill Company, of the same place,) have invented certain new and useful Improvements in Convertible Railway-Cars, of which the following is a specification.

10 My invention has relation to means for expeditiously and economically converting an open car (more especially of the street or surface type) into a closed car, or, vice versa, converting a previously-open car which has 15 been converted into a closed car again into an open car; and my invention has more special reference to providing cars not originally constructed as convertible cars with means for readily converting them into open 20 or closed type.

My invention resides in the novel construction and combination of parts hereinafter described, and pointed out in the claims.

In the drawings forming part of this specification, Figure 1 is a side elevation of a portion of an open car having one of its side openings open and another adjacent side opening converted or closed. Fig. 2 is an elevation, partly in section, on the line $x-x$, Fig. 1. Fig. 3 is a sectional elevation on the line $y-y$, Fig. 1. Fig. 4 is a transverse section on the line 4-4, Fig. 1. Fig. 5 is a like view on the line 5-5, Fig. 1. Fig. 6 is a front view of the window sash or framing, with the 25 detachable securing-strips shown detached and at the sides of the sash or frame. Fig. 7 is a front elevation of the lower panel-slats detached from each other, and Fig. 8 is a front elevation of the sheet-metal lining or 30 covering for the lower panel broken in the center to save room in illustrating.

Similar reference characters indicate corresponding parts throughout the several views.

45 I have illustrated my improvements in connection with an open car of conventional construction.

One of the important features of the present invention resides in the fact that the means 50 which I have invented for converting the car

are readily applicable to most forms of cars in which grooved posts or stanchions are employed extending between the car-sill and the roof, which posts or stanchions delimit the longitudinal extent of each of the side openings of the car, said openings vertically being defined by the roof and sill. My improvements also in part may be applied to a car having side openings between the posts and below the roof and a lower pane, either fixed 55 or movable, extending down to the sill or flooring.

In view of the foregoing I do not limit myself to the precise construction of cars in which my improvements may be embodied. 60

The car illustrated herein has a roof-section 1, comprising the usual members—viz., the roof 2, head-lining 3, rafter 4—all hereinafter generically termed the "roof" or "roof-section," and the outside longitudinal letter-board 5, 70 the outer longitudinal side sills 6, (it being understood that both sides of the car are constructed identical,) the posts or stanchions 7, extending between the roof and to the sills, along the upper ends of which the letter-board 75 extends, the car-flooring 8, the transverse seats 9, extending between the posts, the pivoted seat-back 10, adapted to be used in the conventional manner, the cross stay-pieces 11 between the posts below the seats, the seat 80 foot-rails 12, and the metal seat panels or ends 13, lying on the exterior of the posts, the panels being inset into the posts, so as to leave a portion of the outside of its vertical face projecting over and beyond the seat- 85 panels, as at 14, Fig. 2. All of these parts are of conventional or otherwise desired construction. The posts are provided on their lateral and opposing faces with grooves 15, which may extend up beyond the lower edge of the 90 letter-board and into a pocket or recess 16, provided for the reception of a curtain, to be described, and these grooves are continued down to the sills along the outer face of the seat-panels by means of the grooved ribs 17 to 95 the closed end 18 of the groove. The groove 15 may be provided at a point above the seat-panel with a turnout 15^a, extending outwardly, as shown, or inwardly. As these grooves are merely for the purpose of detach- 100

ably securing the panel and sash, hereinafter described, in place, they may be formed as desired. At 19 is the window-sash, of any desired construction, preferably comprising the rigid side, top, and bottom members 20 21 22 and the glass 23, the lower cross-pieces 22 being preferably formed as a panel of some depth to give a permanently closed effect to the car side above the seat-line, the top cross-piece being recessed at 24. At 25, Fig. 7, is the lower panel, hereinafter to be described.

The sash 19 is secured in place by providing strips 26, preferably made of wood, adapted to be secured by the screws passed through holes 27 to the inner faces of the vertical members 20 of the sash and to the sides of the section 22 and to be inserted edgewise into the grooves in the posts in the manner hereinafter described, as indicated in Fig. 4, the order of the steps being immaterial. The strips 26 are preferably shorter than the sash, as indicated in Fig. 6, and their lower edges are inclined at 28, for a purpose hereinafter described. The lower panel comprises a series 25 of wooden or other strips 29, backed by an outer flexible plate 30, of metal, fiber, or other material, the strips being provided with grooves 31 and tongues 32 and superposed upon each other, so as to form an articulated 30 or flexible backing, to which the plate 30 may be secured—say by the top strip 29^a—the bottom strip 29^b resting on the bottom of the groove 15 in the rib 17. This construction enables a car previously constructed without particular reference to means for converting it into an open or closed car to be expeditiously converted into either an open or closed car and to bear when converted into the closed form a strong and substantial resemblance to 40 a car previously constructed as a closed car or to be as readily converted into an open car again and preserving its original character of an open car. The grooves 15 receive a guiding or cross bar 33, attached to the free end of a curtain 34, of any desired construction, the upper end of the curtain being secured to the roller 35, mounted in bearings in the pocket 16. The grooves 15 are ordinarily carried down to the sill through the medium of the grooves 50 formed in the ribs 17, produced upon the exterior of the seat-panel. I therefore avail myself of these grooves for the purpose of detachably securing the window sash or frame in place, and so far as this part of my invention is concerned it is not necessary that the grooves continue down below the seat-panel. In fact, the grooves 15 in the posts can terminate at any desired distance above the sills or flooring, for the reason that this part of my invention can be employed in what is called "semi-convertible" cars, where there is a fixed panel extending from the flooring to and above the seat-levels.

As illustrating the manner of employing my invention in its various phases and considering that the window frame or sash is to be applied to a semiconvertible car having a

lower fixed panel, such as 25, and openings between the same and the letter-board or roof and between the posts, adapted to be temporarily closed, as by the curtain 34, it will only be necessary to place the window-sash 19 between the posts, closely fitting the sides of the sash against the sides of the posts, as indicated in Fig. 4, and simultaneously or previously inserting the edging-strips 26 in the grooves and securing both the frame and the strips together by screws 36, passing through the previously-prepared apertures in the strips. It is immaterial whether the screws 80 pass from the outside of the frame or inside of the strips. In placing the frame between the posts its upper end is passed underneath the lower edge 37 of the letter-board, so that the recess 24, formed in its upper cross-piece 85 21, will interlock with the lower edge or corner 37 of the letter-board, Fig. 3, thereby holding the frame or sash in position at the top. By making the lower section 22 of the window-frame simulate a panel I can dispense with the necessity of using fixed side paneling above the seat panels or ends, where free access to the posts in the grooves can be readily had, so that this part of my invention can be readily availed of for use in cars having fixed lower paneling of any desired height. Of course the car can be originally constructed to coöperate with my improvements; but my invention in its several aspects has particular application to open cars of the usual type not 95 so previously constructed. In employing the lower panel 25 and setting it within the grooves formed in the ribs of the seat-panels the flexible or articulated connection of the slats with each other and the flexible nature 100 of the sheet-metal or other covering permits it to be disposed in conformity with the curve of the seat end, it being customary to make the lower section of the car curved, as indicated, both the ends of the slats and the flexible sheet extending into the groove, so as to 105 make a non-rattling and weather-tight fit. The panel 25 is placed in position by inserting it as a unit or the slats separately and then the sheet 30 into the grooves 15 in the 110 opposing posts. To do this, either the seat-panel or the rib 17 may be removed; but to avoid this I avail myself of the turnouts 15^a, into which the lower panel as a unit or in pieces or sections may be inserted and moved 115 down the grooves 15 to the end of the grooves, as shown in Figs. 1 and 3. In this way I provide the grooves 15 with detachable elements, permitting of the insertion and removal of the lower panel 25. When the panel 25 is in 120 place, the window sash or frame may be secured in place, as before described. In the specific construction illustrated herein the lower end of the sash 19 will overlap the upper edge of the lower panel, as at 38, Fig. 3. When in this position, the screws 39 are 125 passed through previously-formed apertures 40 in the upper strip 29^a and screwed home into the lower edge of the sash, as indicated 130

in Fig. 3, the lower edge 28 of the edging strips 26 resting upon the inclined surface 42 of the top strip and conforming to its contour, so as to not only support the weight of the window-sash upon the lower panel, (the latter bearing against the bottom 18 of the groove in the seat-panel and against the sills,) but making a good fit, the lower strip 29^b being recessed at 43 to fit over the edge of the sills.

10 to make a weather-tight joint. The purpose of making the edging-strips shorter than the window-frame is thus made apparent.

It is clear that the improvements herein described can be variously employed and embodied in structures differing from that illustrated herein without departing from the spirit of my invention.

When the window-frame is not secured to the car side, the curtain may be employed to close the opening either from the roof to the lower panel or to the flooring when no lower panel is employed, and the lower panel as constructed herein may be permitted to remain a permanent part of the car.

25 Having described my invention, I claim—

1. In a car, the combination with the posts, grooves formed in the posts, of a window sash or frame, and means adapted to be detachably secured to the frame or sash and inserted into said grooves for detachably securing the sash or frame to the posts.

2. In a car, the combination with the side posts having grooves formed therein, of a sash adapted to fit between said posts, and 35 strips carried by said sash fitting into said grooves to removably secure said sash between said posts.

3. In a car, the combination with the grooved side posts, of a sash fitting between 40 said posts and detachably secured in position by extensions removably secured upon the vertical edges of said sash, adapted to fit into said grooved side posts.

4. In a car, the combination with the posts, 45 grooves formed in said posts, of a window frame or sash, and separable strips adapted to be secured detachably to the sash or frame and inserted in the grooves, substantially as described.

5. In a car, the combination with the posts, 50 grooves formed in said posts, of means for closing the openings between the posts comprising a window frame or sash; separable strips adapted to be detachably secured to the sash or frame and inserted in the grooves,

and a panel adapted to be detachably secured in the car side below the said sash or frame.

6. The combination in a car having posts or stanchions provided with opposing grooves, of a sash or frame, separable strips adapted to be inserted in said grooves and secured to the sides of the sash, and a lower panel secured to the car side, substantially as described.

7. In a car, the combination with the lower panel, the upright posts having grooves above the panel, the window sash or frame, the strips inserted in the grooves and secured to the sash, said strips being adapted to rest upon the top of the lower panel, the lower 70 edge of the sash overlapping the upper edge of the panel, the panel and sash being secured together at the overlapping point.

8. The combination with the grooved posts, the lower panel, the window-sash, the strips 75 inserted in the grooves and resting on the lower panel, and means for detachably securing the strips to the sash.

9. The combination in a car having grooved posts, of the lower panel, the window-sash having a recess at its upper cross member, a letter-board extending along the post below the roof, its lower edge being adapted to enter into the said recess, and means for detachably securing the window-sash to the posts 85 and the lower panel.

10. In a car, the combination of posts having grooves, of a lower panel comprising a plurality of longitudinally-disposed strips, an outer flexible covering supported in said 90 grooves, and a window sash or frame detachably secured between the posts and to the upper strip of said lower panel.

11. In a car, the combination with the posts having grooves, the seat-panel having exterior grooved ribs, the grooves in the ribs aligning with the grooves in the posts, a panel in said seat-panel grooves comprising a flexible sheet and a series of transverse strips supported in said grooves, and a window sash or 100 frame detachably secured to the posts and to the seat-panel.

Signed at the city of Philadelphia, county of Philadelphia, and State of Pennsylvania, this 9th day of December, 1901.

EZRA SANGER BUCKNAM.
